INCLINED GALLEY SLIDE ARRESTER

Frank F. Hartlage, New York, N. Y.

Application March 25, 1954, Serial No. 420,570

6 Claims. (Cl. 199—61)

This invention relates to an inclined galley slide arrester for line casting composing machines.

It is an object of the present invention to provide for a line casting composing machine having an inclined galley, an arrester arranged underneath the end of the galley to catch the slide upon the same leaving the end of the galley and to prevent the same from being dropped on the floor and under portions of the machine inaccessible to the operator without difficulty and thereby to increase the efficiency of the operator running such machines.

It is another object of the invention to provide an attaching clamp for an inclined galley slide arrester that is so constructed and formed as to permit the attachment of the arrester to different shape vertically extending frame pieces or posts that differ with the different types of composing machines and thereby to have the arrester adapted for universal use and without having to provide different attaching devices for the respective different machines.

It is another object of the invention to provide in an inclined galley slide arrester for composing machines a spring support extending from the attachment and adapted to hold the catch apron in the proper position under the end of the galley to catch the slide and adapted to be lowered to facilitate and make easy the removal of the slide once it has been caught by the arrester.

Other objects of the invention are to provide an inclined galley slide arrester for line casting composing machines having the above objects in mind, which is of simple construction, inexpensive to manufacture, has a minimum number of parts, easy to mount upon the line casting machine, durable and compact, easy to adjust, of pleasing appearance, effective and efficient in operation.

For other objects and a better understanding of the invention, reference may be had to the following detailed description taken in connection with the accompanying drawing, in which:

Figure 1 is a front elevational view of the inclined galley slide arrester embodying the features of the present invention and illustrating the manner in which the same is attached to the composing machine, and the relationship of the same to the galley forming a part of the machine, the slide block being shown in full and operable over the galley;

Fig. 2 is a perspective view of the galley slide arrester attached to the vise frame forming a part of the machine;

Fig. 3 is a transverse sectional view of the attaching clamp and of the frame as viewed on line 3—3 of Fig. 2;

Fig. 4 is a fragmentary sectional view, in elevation, taken through the clamp and as viewed on line 4—4 of Fig. 3.

Referring now to the figures, 10 represents a vise frame forming a part of a line casting composing machine. This frame piece varies in size for the different types of machines and is generally of rounded corner formation. This frame supports a first elevator slide 11, a knife spring plate 12 and a knife block 13. The cast slugs are made and formed in the machine and are delivered to a galley 14 that extends across the front of the machine and in front of the vise frame. These slugs are indicated at 15 and they are discharged to the galley 14 by the operation of a slug lever 16 in the well known conventional manner. A spring keeper 17 holds the slugs from moving.

Operable over the galley 14 is a galley slide block 18, shown in full, and which has a spring clip 19 that ex-

2

tends over the upwardly extending lip or bottom ledge of the galley. This lip or edge is indicated at 20. The galley bottom is inclined downwardly and forwardly from the front of the machine and the rear thereof is elevated to the front thereof and is without a lip or ledge. The slugs are retained in the slide by the front upturned lip or ledge 20 and by the action of gravity and will rest in an inclined manner upon the galley and against the slide.

10 If the slugs are allowed to accumulate upon the galley to too great an extent so that the slide block 18 is pushed off end 14' of the galley, the galley slide arrester of the present invention and indicated generally at 21 will catch the slide and prevent the slide from falling to the floor into an inaccessible place. Upon the arrester catching the slide, the same will be readily available to the operator and can be quickly replaced upon the galley, after being emptied of slugs.

This galley slide arrester that forms the subject matter of the present invention comprises a bracket assembly 22 that assists in securing the arrester to vise frame piece 10 at the proper elevation, a forwardly extending pivot arm 23 extending outwardly from the bracket and supported by tension spring 24 at a catch apron 25, that extends beneath the galley and outwardly beyond the end 14' thereof, in the manner shown in Fig. 1.

The bracket 22 will extend vertically along the front edge of the frame piece 10 and is secured to the frame piece by a box arrangement 26 that is adaptable to different sizes and contours of the frame piece. This box arrangement includes the lower end of the bracket 22 that extends across the front of the frame piece and has further a thick L-shaped member 27 that extends along one side of the post and across the rear thereof.

35 On the opposite side of the post there is connected a thin and bendable plate piece 28 that is secured by screws 29 to the vertical edge of the rear portion of the thick L-shaped member 27.

Between the edges of the member 22 and the inner faces of the member 27 and the plate 28, there are disposed shims 30, the number depending upon the thickness or width of the frame piece 10. Each of these shims 30 has a laterally extending opening 31 and a vertically extending slot 32 to respectively accommodate 40 upper and lower clamping bolts 33 and 34 extending through the bracket 22, the number 27 and the plate 28, and is tightened by wing nuts 35.

To position the box assembly 26 fore and aft on the frame piece 10, vertically spaced set screws 36 are threaded into the bracket 22 and may be tightened against the front edge of the frame piece 10. This will draw the rear end of the box arrangement 26 against the rear edge of the frame piece 10 to have a tight frictional grip on the rear edge of the framepiece. The plate 28 is also preferably thin so that it can fit into the narrow space that is provided in this area on some machines. The galley slide arrester attaches to line casting composing machines without interfering with any of the adjusting or movable parts of the machine.

50 Extending laterally from the thick member 27 is a pivot pin 37 on which arm 23 pivots. A cotter pin may extend through an opening 38 to prevent the removal of the pivot arm 23 therefrom. This pivot arm is provided with a clamp slot 39 at its outer end between which the apron 25 extends. The portions at the top and bottom of the slot are drawn together by a clamping bolt 40 and a wing nut 41 so as to frictionally retain and hold the apron end within the slot 29 and against lateral displacement therefrom. In holes 55 42 a pin can be extended to further secure and hold the apron member 25 against displacement from the arm 23. The apron will likewise be provided with holes respectively registering with the holes 42 through which the pin can extend.

In order to support the arm 23 and the apron 25 so that the arrester will support the slide and at the same time permit vertical adjustment of the apron relative to the end of the galley, the tension spring 24 extends from one side of the wing nut 44 fixed to a bolt 45 on the arm 23. Extending laterally through the upper end of the bracket 22 is a bolt 46 having a wing nut 47 that

is movable along the bolt to a different position to thereby change the position of the upper end of the tension spring 24. The lower end of the tension spring 24 will have its position changed by turning the nut 44 to a different location. The bolt 45 is held in place by a lock nut 48 and the bolt 46 is held in place by a lock nut 49. By adjusting the wing nuts 44 and 47 along their respective bolts 45 and 46, the arm 23 can be raised or lowered on the pivot pin 37.

The outer end of the catch apron 25 is widened as shown at 51 and this widened portion has a longitudinally extending and upwardly inclined flange 52 and an end flange 53 which will prevent the slide block from falling from the end of the apron. The arrester is elevated so that flange 53 extends up to the bottom of the galley and is outwardly removed a distance slightly greater than the length of the slide block 18. A hole 54 is provided in the end of the apron to permit dirt or dust to escape from the arrester.

It should now be apparent that there has been provided a galley slide block arrester that will prevent the displacement of the slide block from the machine. It will also be apparent that this arrester can be easily connected to the frame piece of a composing machine, even though the shape and size of the framepiece is varied for the different machines and that by a simple adjustment, the catch apron can be positioned at the end of the galley in such a manner as to properly and safely catch the galley slide block should it travel to a point off the end of the galley.

While various changes may be made in the detail construction, it shall be understood that such changes shall be within the spirit and scope of the present invention as defined by the appended claims.

What is claimed is:

1. An inclined galley slide arrester for line casting composing machines which comprises a bracket, means for securing the bracket to the frame of the composing machine, an arm pivotally connected to the bracket and extending forwardly thereof, means for adjustably supporting said arm, means for adjusting the position of the arm to different angular positions relative to the horizontal, and an apron catch member extending laterally from said arm and adapted to be located beneath and beyond the end of the galley.

2. A galley slide block arrester for line casting composing machines comprising bracket means adapted to be attached to a frame piece of the machine, an arm pivotally connected to the bracket means for adjustment with respect thereto, a catch apron connected to said

5 arm and having a flanged end portion adapted when the arrester is mounted upon the machine to extend beyond and below the galley in order to catch the galley slide that may be dropped from the end of the galley.

3. A galley slide arrester for line casting composing machines comprising a bracket adapted to extend along the front of a frame piece of the machine and a box arrangement surrounding the frame piece and including the bracket and having clamping bolt means for drawing the sides of the box arrangement into tight engagement with the sides of the vertical framepiece of the machine, a pivot pin extending outwardly from the box arrangement at one side thereof, a pivot arm pivotally connected to said pivot pin and extending forwardly of the bracket, means for adjustably supporting said pivot arm from said bracket to permit the pivot arm to be lowered or elevated as desired, a catch apron extending laterally from said pivot arm and having a flanged outer end adapted to lie beyond and beneath the open outer end of a galley whereby to catch the slide block upon the same being ejected from the end of the galley.

4. A galley slide block arrester as defined in claim 3, and said means for adjustably supporting the arm upon the box arrangement comprising a laterally extending bolt extending from the bracket and outwardly from one side thereof, an adjustable nut upon said bolt, a tension spring connected to said nut, a bolt extending vertically through the pivot arm and an adjustable nut on said bolt, said tension spring connected to said last mentioned

30 adjustable nut.

5. A galley slide block arrester for line casting composing machines as defined in claim 3, and said box arrangement comprising a thick L-shaped member extending along one side of the frame and across the rear-edge thereof, a thin plate fixed to the rear of the L-shaped member, shims adapted to be disposed between the edges of the bracket and the L-shaped member and the plate, said clamping bolts extending through the bracket, the L-shaped member, the shims and the plate.

40 6. A galley slide block arrester for line casting composing machines, as defined in claim 3, and said pivot arm having a slot in the outer end, said catch apron having a portion extending through said slot and clamping bolt means for securing the apron in said slot, said catch apron having a widened portion and flanges extending upwardly from one side and the end of the widened portion.
